CALCULATOR FOR VALVE MECHANISMS

Ralph D. Bobbitt, Norfolk, Va.

Application January 16, 1939, Serial No. 251,259

11 Claims. (Cl. 235—61)

My invention relates to gauges and has as one of the principal objects thereof the provision of a simple and efficient calculator capable of being adjusted in a manner to denote accurately the adjustment of the valve and eccentric rod of valve mechanisms, for instance, a Walschearte valve motion mechanism employed on locomotives, whereby to equalize the port openings of said valve mechanisms.

Another object of my invention is to provide a calculator of the character described which is simple in construction, durable in use, efficient in operation and economical in manufacture.

Other objects and advantages will be apparent from the following description, appended claims and annexed drawings.

Referring to the drawings wherein like reference characters designate like parts throughout the several views:

20 Figure 1 is a top plan view of my invention.

Figure 2 is a side elevation thereof.

Figure 3 is a sectional view taken on the line 3—3 of Figure 2.

Figure 4 is a sectional view taken on the line 25 4—4 of Figure 2.

Figures 5 to 9 inclusive are diagrammatic top plan views illustrating the various steps in adjusting my novel form of calculator for computing the adjustments to be had in the valve 30 and eccentric rods of a valve motion mechanism.

Figure 10 is a bottom plan view of my invention.

Figure 11 is a side elevation, partly in section, of a valve mechanism to which my invention is 35 applicable.

Figures 12 and 13 are diagrammatic sections of said valve mechanism illustrating the forward and rearward motions respectively of the valve member relative to the valve ports.

40 In practicing my invention, I provide a calculator 4 comprising an elongated plate 5 fashioned with a lengthwise extending channel 6 formed in the upper face thereof. The side walls of said channel are undercut and receive ribs 7 formed on the sides of a slide 8 slidably mounted in said channel.

The plate 5 is provided on opposite sides of the slide with the characters F and R denoting the forward and rearward motions of a valve 50 mechanism V, for instance a Walschearte valve motion diagrammatically illustrated in Figures 11, 12 and 13. Said sides of said plate are hereinafter referred to as the forward and rearward motion sides respectively. The marginal edges 55 of the plate are provided on the front face there-

of and on the forward and rearward motion sides with scales 10 and 11 for indicating the diameters of the front and rear valve ports FVP and RVP respectively, of said valve mechanism in accordance with both the forward and rearward motions of the valve VM of the valve mechanism, respectively. Said scales 10 and 11 are graduated in fractions of inches by means of scale marks 12 and 13 respectively and which are indicative of fourths, eights, sixteenths, 10 thirty-seconds and sixty-fourths of an inch for a purpose hereinafter made apparent. Adjacent the slide 8 and on the forward motion side of the plate, indicated by the character F, are spaced scales 14 and 15 denoting in fractions of an inch 15 valve rod adjustments of said valve mechanism.

The scales 14 and 15 are each divided into a pair of sections having groups of scale readings or marks 16 and 17 indicative of lengthening and shortening adjustments respectively of the valve 20 rod VR of said valve mechanism V. The groups are indicated thereon by the characters L and S respectively etched or otherwise formed on the plate. Intermediate marks 18 divide the sections of said scales 14 and 15 into said groups 25 and are indicated by the characters O denoting a zero or non-adjustment position of the valve rod VR.

The ends of the slide are provided with the characters R and L indicative of the right and 30 left ends of said slide respectively. The slide 8 is also provided with pointer marks 19 and 20 for registry with the scales 14 and 15 respectively. The slide 8, intermediate the ends thereof, has fixed thereto a threaded shaft 21 extending outwardly and upwardly therefrom and on which is rotatably mounted a dial 22. The outer end of said shaft 21 is provided with an adjustable lock nut 23 to permit adjustment of the dial relative to the slide whereby to clamp said 40 dial in fixed position relative to the slide.

The dial is of a sufficient circumference whereby the marginal edge thereof overlies adjacent portions of the plate 5 as clearly illustrated in Figure 1 and for a purpose hereinafter set forth. 45

The dial is provided with radially extending marks 24, 25, 26 and 27, the marks 24 and 25 being indicative of the rear and front ports on forward motion of the valve and the marks 26 and 27 indicative of the rear and front ports on 50 rearward motion of said valve. Said marks 24 and 25, of the forward motion, and 26 and 27, of the rearward motion, are disposed towards the scales 10 and 11 respectively for registry with the marks or readings 12 and 13 thereon. 55

Also, on the dial 22 are marks 23 and 29 coacting with scale markers 30 and 31 respectively and hereinafter set forth.

Adjacent the dial 22, the slide 8 is provided with 5 transversely extending scales 32 and 33 for coaction with oppositely disposed marks 32a and 33a formed on the dial for indicating adjustments of the eccentric rod ER of the valve mechanism.

10 As in the instance of the scales 14 and 15, the scales 32 and 33 are divided into sections having groups of marks 34 and 35 denoting lengthening and shortening adjustments of the eccentric rod of the valve mechanism and are indicated by the 15 characters L and S respectively, etched or otherwise provided on said slide. The intermediate marks 36 of said scales are indicated by the character O indicating zero or non-adjustment position of the eccentric rod.

20 Adjustable secured in the upper face of the plate 5, adjacent the slide 8, is a set screw 37 having a flange 38 overlying the upper face of the slide 8 whereby to clamp said slide relative to the plate for a purpose hereinafter set forth.

25 The marginal edges, on both the forward and rearward motion sides of the plate, have slidably mounted thereon the scale markers 30 and 31 respectively. The markers 30 and 31 are equipped with scale points 39 and 40 respectively 30 and said scale points 39 and 40 coact with the marks 28 and 29 on said dial respectively. The markers 30 and 31 are of a U-shaped construction, the lower arms of which underlie the bottom of the plate and are fashioned with ribs 41 having sliding engagement within slots 42 extending longitudinally of the plate while the upper arms overlie said plate as illustrated in Figure 4 of the drawings. The markers 39 and 31 are formed with pairs of depending ears 43 and 44 respectively, and said pairs of ears 43 and 44 have extending therethrough shafts 45 and 46 respectively. Each of said shafts 45 and 46 are formed with a substantially centrally disposed section having a plane peripheral surface disposed through the respective pair of ears and with right and left-hand threaded sections disposed one on each side of said respective pair of ears for a purpose hereinafter set forth. The 35 marker 39 interposes a pair of auxiliary markers 47 and 48 provided with scale points for indicating the diameters of the rear and front ports respectively on the forward motion of said valve mechanism. The marker 31 likewise interposes a pair of auxiliary markers 49 and 50 for indicating the diameters of the rear and front ports respectively on the rearward motion of said mechanism. The markers 47, 48, 49 and 50 are 40 slidably mounted on the plate in the same manner as the markers 30 and 31 and are fashioned 45 with depending ears 51, 51a, 51b and 51c respectively. The ears 51 and 51a are threaded connected to the threaded sections of the shaft 45 respectively, while the ears 51b and 51c are threaded connected to the threaded sections of the shaft 46 respectively.

50 Interposed between the respective ears of the pairs of ears 43 and 44 (of the markers 30 and 31 respectively) are finger wheels 52 and 53 respectively. The finger wheels 52 and 53 are fixed 55 to the shafts 45 and 46 respectively whereby to effect rotation of said shafts and adjustment of the auxiliary markers as hereinafter set forth. The markers 30 and 31 are provided with set screws 54 and 55 respectively whereby to clamp 60 said markers to the plate.

The auxiliary markers 47, 48, 49 and 50 are provided with set screws 47a, 48a, 49a and 50a respectively for clamping the respective markers to the plate 5 as hereinafter set forth.

5 The under face of the plate 5 is fashioned with a lengthwise extending slot 57 provided with dove-tail shaped side walls 58 whereby to accommodate and maintain therein a card 59 or the like for noting thereon certain adjustment readings hereinafter described.

10 In use—it being the desiratum to equalize the diameters of the port openings of a valve mechanism on both the forward and rearward motion of the valve, for instance, the type used on a locomotive and known as the Walschearte valve 15 motion mechanism and which is illustrated in Figures 11, 12 and 13 of the drawings—the valve movement is checked, for instance from the right-hand side (Figure 11) to ascertain the diameters of the port openings on both the forward 20 and rearward motion of the valve. Assuming, for example, that the diameters of the port openings are as follows: on forward motion the front and rear ports open $\frac{3}{8}$ " and $\frac{1}{8}$ " respectively as illustrated in Figure 12, and on rearward motion 25 the front and rear ports open $\frac{3}{16}$ " and $\frac{1}{16}$ " respectively as illustrated in Figure 13. Having thus ascertained the dimensions of the port openings, my calculator is then adjusted in accordance therewith and operated in a manner to denote the adjustments of the valve and eccentric rods on the mechanism whereby to square or equalize the travel of the valve and which denotation is obtained in the following manner and inasmuch as the dimensions of the ports on both 30 the forward and rearward motions were computed from the right side (Figure 11) of the locomotive, the right-hand scales only on the calculator are used. Obviously, should the dimensions of the ports be computed from the left side of the 35 locomotive, the scales on the left side of the calculator would be used.

40 The initial step is the setting of the various parts of the calculator to zero positions as clearly illustrated in Figure 1 and which involves tightening the lock nut 23, flanged set screw 37, and set screws 47a, 48a, 49a, 50a, 54 and 55 to clamp the dial 22 to the slide 8, the latter to the plate 5, and the respective markers to the plate. After the parts of the calculator are thus positioned, 45 the set screws 47a and 48a of markers 47 and 48 are loosened and the markers 47 and 48 are moved in opposite directions, by means of the finger wheel 52, and with the marker 48 moving towards the right-hand end of the calculator 50 until the pointer thereon registers with the scale mark 12 denoting $\frac{3}{8}$ " from the point on the scale 16 indicated by the mark 25 on the dial as 55 illustrated in Figure 5. This adjustment is indicative of the $\frac{3}{8}$ " diameter opening of the front 60 port on the forward movement of the valve. It is to be understood that movement of marker 47, in the opposite direction and the same distance as marker 48 with respect to the marker 30, is merely coincidental to permit rotation of the 65 shaft 45.

70 The screw 48a of the marker 48 is then tightened and the screw 54 of the marker 30 loosened, whereupon the finger wheel 52 is rotated to move the markers 30 and 47 with respect to the marker 48, through the medium of the shaft 45, and in a direction for registry of marker 47 with the marking 12 on the scale 16 denoting $\frac{1}{8}$ " from the dial marking 24 and which $\frac{1}{8}$ " is indicative 75 of the diameter of the rear port on said forward 75

motion as illustrated in Figure 6. In this position the set screws 47a, 48a and 54 are tightened to hold said markers clamped to the plate.

The set screws 49a and 50a of the markers 49 and 50 are then loosened and the markers 49 and 50 are moved in opposite directions, by means of the finger wheel 53, and with the marker 50 moving towards the right-hand end of the calculator until the pointer thereon registers with the scale 10 marking 13 on the scale 11 denoting $\frac{1}{16}$ " from the point on the scale 11 indicated by the dial mark 27 on the dial 22 as illustrated in Figure 7 of the drawings and which adjustment of the marker 50 is indicative of the $\frac{1}{16}$ " diameter opening of the front port on the rearward motion of the valve. It is to be understood that the movement of the marker 48 in the opposite direction and the same distance as the marker 50 with respect to the marker 31 is merely coincidental 20 to permit rotation of the shaft 46. The set screw 50a on the marker 50 is now tightened and the set screw 55 of the marker 31 loosened, whereupon the finger wheel 53 is rotated to move the markers 31 and 49 with respect to the marker 50, 25 through the medium of the shaft 46, in a direction for registry of the marker 49 with the marking 13 on the scale 11 for denoting $\frac{1}{16}$ " from the dial marking 26 and which $\frac{1}{16}$ " is indicative of the diameter of the rear port on said rearward motion of the valve as illustrated in Figure 8 of the drawings. Having thus adjusted the markers, the latter are maintained in the foregoing calculated positions by the tightening of their respective set screws whereby the computing operation of the calculator may be completed as hereinafter set forth.

When the calculator is thus set, the set screw 37 and the nut 23 are loosened and the slide is moved towards the right and the dial 22 rotated until the dial marks 28 and 29 are aligned with the pointers 39 and 40 respectively of the markers 30 and 31, as illustrated in Fig. 9, whereupon the set screw 37 and the nut 23 are tightened to maintain the slide 8 in fixed relation with the plate 5 and the dial 22 in fixed relation with respect to the markers 30 and 31. Having thus aligned the marks 28 and 29 with the points 39 and 40, the marks 32a and 33a on the dial will indicate scale readings on the scales 32 and 33. 50 Inasmuch as the measurements of the valve ports are taken from the right-hand side thereof, the right-hand scale 33 only is utilized and in accordance therewith reference is had only to the mark 33a of the dial. By observing the mark 20 55 on the slide, it will be noted that it indicates $\frac{1}{32}$ " in group 16 denoting $\frac{1}{32}$ " lengthening of the valve rod VR. Mark 33a on the dial will, in group 33, denote that the valve must be moved forward $\frac{1}{32}$ " in addition to the $\frac{1}{32}$ " indicated by the mark 20 60 in group 16. This is accomplished by the eccentric rod ER, Figure 12, whose ratio in relation to the valve VM, Figure 12, in this instance is four to one. Therefore, the eccentric rod ER is lengthened four times $\frac{1}{32}$ " or a total of $\frac{1}{8}$ ". 65 These readings are now written on the card 59 as follows: "Lengthen eccentric rod $\frac{1}{8}$ ", and "Lengthen valve rod $\frac{1}{32}$ ", as clearly shown in Figure 10. By adjusting the valve and eccentric rods in accordance with these readings, the dimensions of the port openings on both forward and rearward motions will be equalized or squared.

From the foregoing it will be apparent that I have provided a simple and reliable calculator 70 whereby the port openings of a valve mecha-

nism may be readily adjusted to equal diameters through the medium of computing the adjustments of the valve and eccentric rods.

It is obvious that the invention is not confined to the herein described use therefor as it may 5 be utilized for any purpose to which it is adaptable. It is therefore to be understood that the invention is not limited to the specific construction as illustrated and described, as the same is only illustrative of the principles of operation 10 which are capable of extended application in advance forms, and that the invention comprehends all construction within the scope of the appended claims.

What I claim is:

1. In a calculator, means for dimensionally indicating premeasured positions of a valve with respect to the front and rear ports of a valve mechanism upon forward and rearward motion of said valve, means for dimensionally indicating calculable positions of said valve with respect to said ports to equalize opening and closing of said ports upon said motion, and means for co-ordinating said first and second mentioned means to determine factors useful in the calculation of the differentials between said first and second mentioned positions and to dimensionally indicate said differentials whereby said valve may be adjusted in accordance with said differentials to effect said equalized opening and closing of said ports.

2. In a calculator, a pair of relatively movable elements, means on one of said elements for dimensionally indicating premeasured positions of a valve with respect to the front and rear ports of a valve mechanism upon forward and rearward motion of said valve, means on both of said elements for dimensionally indicating calculable positions of said valve with respect to said ports to equalize opening and closing of said ports upon said motion, and means on the other of said elements for coordinating said first and second mentioned means to determine factors useful in the calculation of the differentials between said first and second mentioned positions and to dimensionally indicate said differentials whereby said valve may be adjusted in accordance with said differentials to effect said equalized opening and closing of said ports.

3. In a calculator, a pair of relatively adjustable elements, one of said elements provided with scale indicia, a plurality of relatively adjustable markers adjustably mounted on said last mentioned element and coacting with said indicia for dimensionally indicating premeasured positions of a valve with respect to the front and rear ports of a valve mechanism upon forward and rearward motion of said valve, means on both of said elements for dimensionally indicating calculable positions of said valve with respect to said ports to equalize opening and closing of said ports upon said motion, and means on the other of said elements and coacting with certain of said markers and said second mentioned means to determine factors useful in the calculation of the differentials between said first and second mentioned positions and to dimensionally indicate said differentials whereby said valve may be adjusted in accordance with said differentials to effect said equalized opening and closing of said ports.

4. In a calculator, a pair of relatively adjustable elements, means on one of said elements for dimensionally indicating premeasured positions

of a valve with respect to the front and rear ports of a valve mechanism upon forward and rearward motion of the valve by the eccentric and valve rod members of said mechanism, means 5 on said elements for dimensionally indicating calculable adjustments of said members respectively to equalize opening and closing of said ports by said valve upon said motion, and means 10 on the other of said elements for coordinating said first and second mentioned means to determine factors useful in the calculation of the differentials between said positions and said 15 adjustments and to dimensionally indicate said differentials whereby said valve may be adjusted in accordance with said differentials to effect said 20 equalized opening and closing of said ports.

5. In a calculator, a pair of relatively adjustable elements, one of said elements provided with scale indicia, a plurality of relatively adjustable 20 markers adjustably mounted on said last mentioned element and coacting with said indicia for dimensionally indicating premeasured positions of a valve with respect to the front and rear ports of a valve mechanism upon forward and 25 rearward motion of said valve by the eccentric and valve rod members of said mechanism, means on said elements for dimensionally indicating calculable adjustments of said members respectively to equalize opening and closing of said 30 ports by said valve upon said motion, and means on the other of said elements and coacting with certain of said markers and said second mentioned means to determine factors useful in the 35 calculation of the differentials between said positions and said adjustments and to dimensionally indicate said differentials whereby said valve may be adjusted in accordance with said differentials to effect said equalized opening and closing of said ports.

40 6. In a calculator, a pair of relatively movable elements, means on one of said elements for dimensionally indicating premeasured positions of a valve with respect to the front and rear ports of a valve mechanism upon forward and 45 rearward motion of the valve, means on said elements for dimensionally indicating calculable positions of said valve with respect to said ports to equalize opening and closing of said ports upon 50 said motion, and means on the other of said elements and including a rotatable member and scale indicia for coordination with said first and second mentioned means to determine factors useful in the calculation of the differentials between said first and second mentioned positions 55 and to dimensionally indicate said differentials whereby said valve may be adjusted in accordance with said differentials to said second mentioned position.

7. In a calculator, a plate, a slide mounted on 60 said plate and adjustable relative thereto, scale indicia on said plate, markers adjustably carried on said plate and coacting with said indicia for dimensionally indicating premeasured positions of a valve with respect to the front and rear 65 ports of a valve mechanism upon forward and rearward motion of the valve by the eccentric and valve rods of said mechanism, scales on said plate and slide for dimensionally indicating calculable adjustments of said rods respectively

to equalize opening and closing of said ports by said valve upon said forward and rearward motion, a scale mark on said slide and coacting with one of said scales upon relative movement of said slide and plate to denote dimensional 5 adjustments on one of said rods, and a member rotatably mounted on said slide and having a scale marking coacting with certain of said markers and said other scale to denote dimensional 10 adjustments on the other of said rods. 10

8. A valve setting calculator comprising a plate having scaled indicia thereon indicative of the forward and rearward motion of a valve for opening and closing front and rear valve ports of a valve mechanism including eccentric and 15 valve rod members for operating said valve, said plate provided with scale markings denoting a setting position of one of said members; a slide mounted on said plate and formed with scale markings denoting a setting position of the other 20 of said members, adjustable markers carried by said plate and coacting with said indicia for indicating premeasured positions of said valve, means carried by said slide and movable relative thereto for coaction with said markers and 25 said markings on said slide for indicating adjustment of one of said members, and means on said slide and movable therewith for coaction with said markings on said plate to indicate adjustment of the other of said members whereby 30 said members may be adjusted in accordance with both of said adjustments respectively to effect positioning of said valve in a manner to open and close said ports equally on both the forward and rearward motion of said valve. 35

9. A valve setting calculator comprising a plate having scaled indicia thereon indicative of the forward and rearward motion of a valve for opening and closing front and rear valve ports of a valve mechanism including eccentric and 40 valve rod members for operating said valve, said plate provided with scale markings denoting a setting position of one of said members; a slide mounted on said plate and formed with scale markings denoting a setting position of the other 45 of said members, adjustable markers carried by said plate and coacting with said indicia for indicating premeasured positions of said valve, a rotatable dial carried by said slide and movable relative thereto and provided with marks for coaction with said markers and said markings on said slide for indicating adjustment of one of said members, and a mark on said slide and movable therewith for coaction with said markings on said plate to indicate adjustment of the 50 other of said members whereby said members may be adjusted in accordance with both of said 55 adjustments respectively to effect positioning of said valve in a manner to open and close said ports equally on both the forward and rearward motion of said valve. 60

10. The structure of claim 3 as set forth and defined therein including, means for clamping said slide to said plate.

11. The structure of claim 9 as set forth and defined therein including, a set screw carried by said plate and openable for clamping said slide in fixed position with respect to said plate. 65

RALPH D. BOBBITT.
